COVERING FOR CABLES AND THE LIKE.

Application filed July 2, 1927. Serial No. 203,001.

This invention relates to improvements in coverings for cables and the like and aims to provide an expandable and contractible sheath adapted to serve as an anchorage or reinforcement for cement or other suitable fireproofing or heat insulating material or other plastic coating.

The invention will be apparent from the following specification when read in connection with the accompanying drawings and the features of novelty will be pointed out with particularity in the appended claim.

In the drawings—
Fig. 1 shows an electric cable having a covering embodying our invention;

Fig. 2 is a similar view on a smaller scale showing the application of our covering to a cable having an enlarged joint;

Fig. 3 is an enlarged detail showing our improved expandable and contractible sheath and the woven arrangement of the strands thereof.

Heretofore, the application of fireproofing materials to lead covered cables and the like has always been a laborious process. Several methods are in vogue for applying the materials, most of them involving a tedious hand-wrapping operation. The common rope and cement mortar combination involves the spiral wrapping of a $\frac{1}{4}$ inch hemp or jute rope at a $\frac{1}{4}$ inch spacing around the cable to serve as a base and binder for the cement mortar which is plastered on to a total thickness of $\frac{5}{8}$ to $\frac{3}{4}$ inches. Another type of binder used with cement mortar is a wire lath provided with clay buttons. This is wound on spirally in strips about 3 inches wide. It is not only a laborious process but the ends of the lath wires form a source of danger to the hands of the workmen. Another common fireproofing material is asbestos tape in various forms used either with or without a cement mortar. A fourth method is the use of a cement mortar applied directly to the cable with a binding tape wound spirally around the outside. All of these prior practices involve a tedious hand-wrapping operation.

To overcome the inefficient and time consuming hand-wrapping of cables, we provide a sheath which is so woven that it can be readily expanded to permit its being easily and freely slipped over the cable or any joints therein and then contracted by an end-wise pull to hug the surface of the cable.

Our improved sheath S is of tubular stocking-like form made up of loosely woven diagonally disposed strands 10 and 12 which cross one another at an angle so as to form a coarse open-work mesh as illustrated in Fig. 3. The strands 10 and 12 are preferably made of asbestos rope and the intersecting ends are bound together with twine as indicated at 14.

The diagonal arrangement of the strands causes the stocking-like tubular sheath S when compressed longitudinally, to expand or enlarge the diameter of the sheath and enables it to be readily slipped over the end of the cable.

This expandable character of the sheath is of particular advantage where a spliced or jointed cable is to be covered with fireproof cement.

Figure 1 shows a cable C a portion of which is covered with a layer of cement or fireproofing compound F which is applied over the open-work sheath S. The left part of this figure shows the sheath expanded and illustrates how part of it can be slipped out of the way for the purpose of making a joint or splice in the cable.

Fig. 2 illustrates a cable which has been spliced at the enlarged joint J. The fireproofing cement F is adapted to cover the entire joint as well as the right half of the cable but the same has been broken away and omitted in the drawing to show the manner in which the sheath S fits snugly over the enlarged joint as well as the cable proper.

The woven sheath shown and described is of tubular or stocking-like form but I contemplate also using a diagonally woven flat fabric on cables which have been joined or spliced prior to the time of covering with a fireproofing coat. On such work, the flat mesh fabric will be wrapped about the cable and the edges drawn together and fastened by a suitable lashing cord.

While the expandable sheath has been shown and described in connection with the fireproofing of cables, it will be readily understood that the same can also be used in connection with the application of heat insulation material to pipes for conveying fluids, and generally to the coating of cables, pipes and the like with plastic material.

Various other modifications may be made by those skilled in the art without departing

from the invention as defined in the appended claim.

What we claim is:—

In combination, a lead covered cable having an outer covering comprising a stocking-like sheath of oppositely inclined interwoven strands and a layer of fireproof cement em-

bedded between said strands and surrounding said sheath.

In witness whereof, we have hereunto signed our names.

ALLEN D. PETTEE.
CARROLL H. SHAW.
